(57) **CLAIM**

The ornamental design for an analyzing instrument and display monitor in combination, as shown and described.

DESCRIPTION

The patent or application file contains at least one drawing executed in color. Copies of this patent or application with

color drawings will be provided by the Office upon request and payment of the necessary fee.

FIG. 1 is an exploded, front perspective view of a first embodiment of an analyzing instrument and display monitor in combination showing our new design, with the display monitor shown detached from the analyzing instrument.

FIG. 2 is a front perspective view of the analyzing instrument and display monitor in combination of FIG. 1, with the display monitor shown attached to the analyzing instrument.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a top plan view thereof.

FIG. 8 is a bottom plan view thereof.

FIG. 9 is an exploded, front perspective view of a second embodiment of an analyzing instrument and display monitor in combination showing our new design, with the display monitor shown detached from the analyzing instrument.

FIG. 10 is a front perspective view of the analyzing instrument and display monitor in combination of FIG. 9, with the display monitor shown attached to the analyzing instrument.

FIG. 11 is a front elevational view thereof.

FIG. 12 is a rear elevational view thereof.

FIG. 13 is a left side elevational view thereof.

FIG. 14 is a right side elevational view thereof.

FIG. 15 is a top plan view thereof.

FIG. 16 is a bottom plan view thereof.

FIG. 17 is an exploded, front perspective view of a third embodiment of an analyzing instrument and display monitor in combination showing our new design, with the display monitor shown detached from the analyzing instrument.

FIG. 18 is a front perspective view of the analyzing instrument and display monitor in combination of FIG. 17, with the display monitor shown attached to the analyzing instrument.

FIG. 19 is a front elevational view thereof.

FIG. 20 is a rear elevational view thereof.

FIG. 21 is a left side elevational view thereof.

FIG. 22 is a right side elevational view thereof.

FIG. 23 is a top plan view thereof; and,

FIG. 24 is a bottom plan view thereof.

The broken lines depict portions of the analyzing instrument and display monitor in combination that form no part of the

(Continued)

claimed design; the broken lines and the unshaded surfaces form no part of the claimed design. In the drawings, the stippled shading represents surfaces having the contrast in appearance shown.
